SPLIT-CYCLE TIMING DEVICE

Joseph F. Kovalsky, Turtle Creek, Pa., assignor
to Westinghouse Electric & Manufacturing
Company, East Pittsburgh, Pa., a corporation
of Pennsylvania

Application October 27, 1934, Serial No. 750,304

5 Claims. (Cl. 175—183)

My invention relates to electric discharge apparatus, and, in one aspect, to such apparatus for measuring time intervals of the order of 1/60 of a second within accuracy limits of the order of 5 1/1200 of a second. For such purposes, my invention is particularly applicable to the measurement of the time of response of high-speed electrical apparatus, such as regulator elements, protective relays and circuit breakers.

10 In its more general aspects, my invention embraces novel methods and apparatus for electrically storing a measured indication and afterward utilizing such stored indication for electrical control or other purposes.

15 In connection with the application of my invention for the measurement of time intervals, recent development in high-speed regulators and in protective apparatus for transmission circuits have led to the introduction of relay elements 20 which operate in a time interval of the order of 1 or 2 cycles of a 60 cycle supply, and of contactors which operate in a time interval of the order of 2 cycles. The performance of such apparatus may be satisfactorily recorded by means 25 of an oscillograph, but the cost of films and of the oscillograph itself, as well as the time and care necessary to obtain comparative results render the use of this instrument objectionable for such purposes.

30 It is an object of my invention to provide a simple direct-reading instrument which will give a numerical indication of the time values sought, without the use of photographic films or similar apparatus.

35 Another object of my invention is to provide a novel direct-reading timing device which will be free from errors caused by the acceleration or deceleration of moving parts.

40 A further object of my invention is to provide novel methods and apparatus for electrically storing measured indications.

45 Other objects of my invention will become evident from the following detailed description taken in conjunction with the accompanying drawing, in which

Fig. 1 is a diagrammatic view of the control circuits used in one embodiment of my invention.

50 Fig. 2 is a diagrammatic view illustrating the optical system of a timing device embodying my invention.

55 Fig. 3 is a time-current curve showing the sequence of discharge of a pair of glow tubes employed in the practice of my invention.

55 Referring to Fig. 1 in detail, a line switch 1

is provided for controlling the connection of a two-pole split-phase synchronous motor 2 and a rectifier transformer 3 to a suitable 60 cycle source (not shown). An external condenser 4 is provided for producing quadrature phase energization of the motor 2, and the latter is provided with a suitable induction starting winding in accordance with the usual practice.

5 The rectifier transformer 3 is provided with a centrally-tapped plate winding 5, connected to 10 the plates of a full-wave hot-cathode rectifier 7, and with a filament winding 6 connected to the cathode of the rectifier 7 in the usual manner.

A filter 9, comprising a shunt condenser 11 and a series reactor 13 is provided for reducing the 15 harmonics in the output of the rectifier 7 and transformer 5 in accordance with the usual practice. It will be understood that the specific filter shown is illustrative only, and that the invention may be practiced with any of a variety 20 of such devices known in the art.

A potentiometer 15, comprising a pair of adjustably-tapped resistors 17 connected in parallel to each other and in series to a third resistor 19, is connected to the output terminals 25 of the filter 9. The potentiometer 15 normally draws a load current which assists in reducing the ripple in the direct current voltage in a manner well understood in the art.

A pair of condensers 21 and 22 are connected 30 to the adjustable taps of the potentiometer 15. The condenser 21 is connected in parallel to a circuit which includes a glow tube 23, a resistor 25 and one pole of a high-speed two-pole manually-operated switch 27. The condenser 22 is connected in parallel to a similar circuit which includes a glow tube 24, a resistor 26 and the contacts of a relay 30, under test. The energizing circuit for the relay 30 includes the remaining pole of the switch 27 and a source (not shown) 35 suitable for energizing the relay under test.

The glow-tubes 23 and 24 are preferably of the two-electrode gas-filled type, having the usual characteristic of becoming conducting at a predetermined value of voltage, and remaining conducting after their initial impedance has been broken down, until a zero value of current occurs. The resistors 25 and 26 serve to limit the current which can flow from the corresponding condenser 21 or 22 when the associated glow tube 23 or 24, respectively, is in conducting condition. The potentiometer 15 supplies a maximum voltage considerably above the break-down voltage of the glow-tubes 23 and 24.

55 Referring to Fig. 2, the glow tubes 23 and 24

are arranged to illuminate an inner dial 31 and an outer dial 32, respectively, on a disc 33 driven by the synchronous motor 2. The entire apparatus is preferably enclosed in an opaque casing 5 (not shown) having windows for viewing the illuminated portions of the dials 31 and 32. An opaque stationary screen 34 is provided for preventing any cross-illumination of the dials 31 and 32 by the glow tubes 24 and 23, respectively.

10 The operation of the above-described apparatus may be set forth as follows: The switch 1 is initially closed thereby energizing the transformer 3 and starting the synchronous motor 2. When the cathode of rectifier 1 becomes sufficiently heated, rectified current is supplied through the filter 9 to the potentiometer 15, and the condensers 21 and 22 become charged to voltages determined by the positions of the corresponding taps of potentiometer 15.

15 20 To initially adjust the apparatus, the switch 21 is closed, thereby causing the closure of the relay 30. If the adjustments of potentiometer 15 are such that the voltages applied to the glow tubes 23 and 24 exceed their breakdown values, the glow-tubes 23 and 24 break down, thereby discharging the condensers 21.

However, as soon as one of the condensers 21 is completely discharged, the voltage applied to the corresponding glow tube 23 or 24 becomes zero, and the initial impedance of the glow tube is reestablished thereby interrupting the condenser discharge current. The deenergized condenser 21 accordingly re-charges exponentially at a rate determined by the resistances of the various paths through the potentiometer 15. When the voltage of the condenser 21 again equals the break-down voltage of the corresponding glow tube, the latter again breaks down and the cycle repeats. If the voltage initially applied to either condenser 21 is insufficient to cause breakdown of the corresponding glow tube 23 or 24, this fact will be evident from a lack of illumination on the corresponding dial 31 or 32. The corresponding tap of the potentiometer 15 is raised 45 to a higher voltage position until breakdown occurs.

The glow tubes 23 and 24 periodically break down at frequencies determined by the positions of the corresponding taps of the potentiometer 50 15. By varying the positions of the potentiometer taps, a stroboscopic effect may be observed when the frequency of the glow tube circuit being adjusted approaches 30 cycles per second. Under these conditions, one flash of the glow 55 tube occurs substantially at each revolution of the disc 33, and the corresponding dial 31 or 32 appears to be slowly rotating. The potentiometer taps are adjusted until both dials 31 and 32 appear to be stationary. When this adjustment 60 is made, the switch 21 is opened, and a short time interval allowed to elapse in order to permit the condensers 21 to become fully charged.

To measure the time of operation of the relay 65 30, the switch 21 is reclosed. Upon closure of the switch 21, the glow tube 23 breaks down substantially instantaneously, and a point on the inner dial 31 is illuminated and appears to be stationary because of the recurring flashes of glow tube 23.

As soon as the relay 30 operates, the glow tube 70 24 breaks down and a portion of the outer dial 32 is similarly illuminated and appears stationary. The time which elapsed between the initial breakdowns of the glow tubes 23 and 24 ap-

pears as the difference of readings of the dials 31 and 32.

Fig. 3 illustrates the character of the successive discharges in glow tubes 23 and 24. In this figure, the current impulses through the tube 23 5 are denoted by the reference character 23', and those through the tube 24 are similarly denoted by the reference character 24'. In order to produce clear definition of the dials, it is necessary that the impulses 23' and 24' be of short time 10 duration. This requires that the resistors 25 and 26 be of comparatively low value, consistent with the safety of condensers 21.

I do not intend that the present invention shall be restricted to the specific structural details, 15 arrangement of parts or circuit connections herein set forth, as various modifications thereof may be effected without departing from the spirit and scope of my invention. I desire, therefore, that only such limitations shall be imposed as are indicated in the appended claims.

I claim as my invention:

1. In a timing device, an optical system comprising an index and a pair of electric illuminating devices capable of producing light pulses of 25 short time duration in response to a predetermined condition of electrical energization, said illuminating devices being arranged in optical paths with said index, timing means for causing said paths to sweep said index, initiating means 30 for producing said predetermined condition in said illuminating devices successively with a time difference dependent upon the magnitude of the time interval to be measured, and electric oscillating means effective upon operation of said initiating means to periodically energize said illuminating devices to said predetermined condition of energization, at the same frequency, with a phase difference corresponding to said time difference, whereby said time interval is translated 40 to a distance interval between repeatedly illuminated portions of said index.

2. In a timing device, an optical system comprising an index and a pair of electric discharge devices capable of producing successive light 45 pulses when energized by a periodically recurring electrical condition, said discharge devices being arranged in optical paths with said index, timing means for causing said paths to sweep said index cyclically at a predetermined frequency, 50 energizing circuits for said discharge devices including individual oscillator means effective to produce periodically recurring electrical conditions of said predetermined frequency in said discharge devices, and means for initiating operation of said energizing circuits successively with a time difference dependent upon the time interval 55 to be measured, whereby said time interval is translated to a distance interval between repeatedly illuminated portions of said index. 60

3. In a timing device, an optical system comprising a rotary index and a pair of electric discharge devices capable of producing successive light pulses when energized by a periodically recurring electrical condition, said discharge devices being arranged to illuminate portions of 65 said index, timing means for rotating said index at a predetermined frequency, energizing circuits for said discharge devices including individual 70 electronic oscillator means effective to produce periodically recurring electrical conditions of said predetermined frequency in said discharge devices, and means for initiating operation of said energizing circuits successively with a time dif- 75

- ference dependent upon the time interval to be measured.
4. In a timing device, an optical system comprising a rotary index and a pair of glow discharge devices arranged to illuminate portions of said index, timing means for rotating said index at a predetermined frequency, energizing circuits for said discharge devices including individual electronic oscillator means effective to produce periodically recurring electrical conditions of said predetermined frequency in said discharge devices, and means for initiating operation of said energizing circuits successively with a time difference dependent upon the time interval to be measured.
5. In a timing device, an optical system comprising a rotary index and a pair of glow discharge devices arranged to illuminate portions of said index, timing means for rotating said index at a predetermined frequency, direct-current energizing circuits for said discharge devices including series resistance elements and shunt capacitance elements effective to produce periodically recurring discharges of said predetermined frequency in said discharge devices, and means for closing said energizing circuits successively with a time difference dependent upon the time interval to be measured.
